UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO.

TICKET-CASE.

1,249,309.

Specification of Letters Patent. Patented Dec. 11, 1917.

Application filed January 13, 1915. Serial No. 1,912.

To all whom it may concern:

Be it known that I, EDWARD KIRBY BOTTLE, a citizen of the United States, residing at Elmira, in the county of Chemung and 5 State of New York, have invented certain new and useful Improvements in Ticket-Cases, of which the following is a full, clear, and exact description, such as will enable others skilled in the art to which it appertains to make and use the same.

This invention relates to record-making devices, and has special reference to such records as sales sheets, sales books, etc.

One of the objects of the invention is the 15 provision of a practical device wherewith permanent records on original and duplicate sheets or slips may be readily made.

Another object of the invention is the provision of a simple device by means of which 20 a record may be made in the single sheet in the operation of tearing the same, and so that the sheet sections will have counterpart records.

Another object of the invention is the 25 provision of a practical recording device having associated therewith a container or receptacle for a record sheet.

Other objects will be in part obvious and in part pointed out hereinafter.

30 The invention accordingly consists in the features of construction, combinations of elements and arrangement of parts which will be exemplified in the construction hereinafter set forth, and the scope of the application of which will be indicated in the following claims.

In the accompanying drawings, forming 35 part of this specification and wherein similar reference characters refer to similar parts throughout the several views,—

Figure 1 is a perspective view of the device, the broken lines showing a severed sheet;

Fig. 2 is a transverse section through 45 Fig. 1;

Figs. 3 and 4 are views of record sheets which may be employed with the apparatus.

It is customary in some places for the purchaser of goods to receive a sheet or slip 50 itemizing the purchase, and totaling the amount of the purchase, this sheet being torn from another or duplicate sheet containing a similar record. The sheet or slip received or shown to the purchaser is often-

times not to be retained by him, but is retained in the custody of the clerk, the duplicate being sent to the cashier or auditor. Chances of error or deception are offered by many of the present systems and one of the main purposes of the present invention is 55 to minimize the occurrence of errors and to lessen the chances of deception without discovery. To this end this invention contemplates the use of a sheet of paper which may be readily torn, such as the record paper 60 found in the ordinary sales book. The sheets are provided with the usual places for writing in the items of the purchase, etc., the price for the purchase, and, in addition, at some portion, is provided one or more 65 columns of figures arranged in series corresponding with, or as closely as possible to, the totals ordinarily paid for the purchase. For instance, on the sheet shown in Fig. 3 70 of the drawings the blank portions represent those parts to be written upon and whereon the clerk may indicate the items purchased, the cost and the total in the usual manner. The columns of figures represent a series corresponding, respectively, either 75 accurately or approximately, to the total cost of purchases customarily made, it being intended that the total amount of the purchase shall be found in said columns, although this is not essential as the approximate 80 amounts of the purchase will obviously be found therein within reasonable limits.

By means of the present invention one or more items appearing in each column may be permanently marked or indicated, as by 85 severing the sheet so that the main portion of one column shall be on one severed section and the main portion of the other column on the other severed section, counterpart marks being made on the respective sections at or 90 opposite the numerals of the columns corresponding to the amount of the purchase. In the present embodiment the sheet is torn on straight lines intermediate the columns, except opposite the numeral indicating the 95 amount of the purchase, and at this point a tongue or tip *a* is left on one section and a counterpart recess *b* on the other. Thus the severed sections are permanently marked by 100 counterpart elements which correspond and are located at definite places on the sections so that the auditor may be able to note 105 whether or not the marking on one sheet is

different from that on another and to this extent take notice of the fact that the sheets are properly or improperly marked.

Referring now more specifically to the drawings, the numeral 1 indicates a main sheet-tearing or severing member having a tearing edge 2, against which a sheet may be manipulated so as to be torn and thereby divided into separate sections. In the preferred embodiment the tearing edge 2 is straight for a greater portion of its length, being interrupted intermediate its ends by an auxiliary sheet-tearing member 3 having preferably two tearing edges 4 and 5 extending at angles to the tearing edge of the main member 1 and to each other. The auxiliary member 3 thus provides a tooth on the main member which projects from the edge of the main member and is preferably located intermediate the ends of the edge 2, as illustrated. The numeral 6 indicates a table on which the sheet to be torn may be placed beneath the tearing members, whereupon the latter may be pressed toward the table 6, so as to cause the sheet to be gripped or held between the tearing members and the member 6 prior to being torn.

In the preferred embodiment the tearing member and the table are associated with a receptacle or container comprising the lateral walls 7 and 8 and the lower wall 9, a portion of the upper wall of the receptacle being formed by the main tearing member 1, as clearly shown. In this receptacle is provided a normally open slot or passageway 10 leading into the interior thereof and through which a portion of a record sheet may be inserted so that the tearing edge 2 extends laterally of the passageway, in the preferred embodiment the main member 1 forming one wall of said passageway, the other wall being comprised of the table 6 which may be regarded as an extension of the wall 8, these members being supported with sufficient rigidity to prevent the abstraction of the contents of the receptacle through the passageway or slot. Thus the passageway 10 is bounded on one side by the tearing member and on the other opposite side by the table 6, this latter member extending outward from the wall of the receptacle at one side of the passageway 10 and also inward beneath the toothed wall for a short distance, so as to provide ample area to grip or hold the sheet. In the preferred construction the walls of the receptacle are metallic and that portion of the upper wall formed by the member 1 is movable toward and from the table 6, said wall 1 being preferably integral with the wall 7 and normally sufficiently spaced from the upper surface of the table 6, so as to permit the sheet to be readily introduced between them and underneath the auxiliary tearing member 3, the resiliency of the metal permitting

the main member 1 to be moved toward and from the table 6, as will be understood. In case the member 1 may not be of sufficient stiffness to effectively grip the sheet throughout its width, it may be reinforced by a metallic plate or member 11 brazed thereto. The lower wall 9 of the receptacle may be provided with a door 12, hinged at 13, and a suitable lock 14 may be employed to fasten the door, so as to prevent unauthorized entry into the receptacle. Different forms of original and duplicate sheets may be employed, two forms being illustrated. In Fig. 3, the sheet is flat and is employed without carbon manifolding devices, the items of purchase being separately written in the proper sections under the heading "Restaurant". One of these sections may be termed the original and the other the duplicate. Intermediate the sheet are two similar columns of numerals corresponding to the purchase total. In Fig. 4 the sheet is folded so that the sections to be written upon are superposed, and the column of numerals on one section is duplicated on the other and lies directly beneath it, the upper section being carbonized on the inner face. Preferably the container is slotted at its ends opposite the passageway 10, as indicated at 15, so as to permit a wide sheet to be easily adjusted in the passageway referred to.

The operation of the apparatus is as follows: A sheet of the character hereinbefore referred to, in which the original and duplicate portions thereof are provided with corresponding similar identifying characters *c* or *d*, has one end placed beneath the member 1, the sheet being manipulated so that the tooth 3 shall come opposite the number in the column corresponding to the total amount of the purchase. In this position one end of the sheet will be inside the receptacle more or less, with the sheet lying upon the table 6. By pressing down the member 1 the sheet may be held in the position to which it has been adjusted and may then be manipulated by the operator so as first to be drawn straight back toward the main tearing edge 2, which movement will result in the tearing of the sheet by the sides of the tooth 3. After such tearing has been accomplished, the sheet may be completely torn apart by being manipulated so as to shear against the straight tearing edge 2, whereupon one end of the sheet will be in the operator's hand while the other end will fall into the container, or may be made to fall therein by a slight shake of the container. In manipulating the form shown in Fig. 4, only the upper section is manipulated in the manner described.

Thus, by the above described construction are accomplished, among others, the objects hereinbefore referred to.

As many changes could be made in the

above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. A record-making device comprising a receptacle having a normally open slot, one edge of which is provided with a tearing member and an auxiliary tearing member integral therewith, said edge being supported with sufficient resiliency to permit said tearing member to be pressed against the opposite edge of said slot and with sufficient rigidity to prevent the abstraction of the contents of the receptacle through said slot, said receptacle being provided with a door through which the contents may be removed, and means for locking said door.

2. A record-making device comprising a receptacle having a slot normally open for the insertion of a ticket therein from the outside, one edge of which is provided with a tearing member and an auxiliary tearing member, said edge being supported with sufficient resiliency to permit said tearing member to be pressed against the opposite edge of said slot and with sufficient rigidity to prevent the abstraction of the contents of the receptacle through said slot, the other side of said slot having attached thereto a support for guiding the sheets as they are inserted in said slot, said receptacle being provided with a door through which the contents may be removed, and means for locking said door.

In testimony whereof I affix my signature, in the presence of two witnesses.

EDWARD KIRBY BOTTLE.
